UNITED STATES PATENT OFFICE.

CHRISTOPHER SCHRAM, OF DENVER, COLORADO.

TENT-COTTAGE AND VENTILATOR THEREFOR.

No. 820,526.

Specification of Letters Patent.

Patented May 15, 1906.

Application filed December 15, 1905. Serial No. 291,901.

To all whom it may concern:

Be it known that I, CHRISTOPHER SCHRAM, a citizen of the United States of America, residing in the city and county of Denver and State of Colorado, have invented a new and useful Tent-Cottage and Ventilator Therefor, of which the following is a specification.

My invention relates to improvements in tent-cottages, and particularly to a combined 10 ventilator and rafter-support therefor, and further contemplates the use of a hinged awning, which forms part of the end of the cottage or house, and of a ventilator just above the floor-level, the same being designed as an 15 improvement over the invention for which Letters Patent were granted to me on the 10th day of January, 1905, No. 779,446.

The object of my present invention is to provide a ventilator which also forms a support for the upper end's of the rafters of the 20 tent and for the rafters which support a flap, the support being so arranged as to provide an air-space between the tent and flap which communicates with the interior of the tent, 25 an additional ventilator in the form of a housing being employed which also communicates with the atmosphere and with the interior of the tent, suitable doors or covers being provided both at the apex of the tent and 30 in the sides of the housing for regulating or cutting off the ventilation, the ventilation being rendered more effective by an air inlet or ventilator of suitable construction located near the floor-line of the house.

35 A further object of the invention is to provide an awning forming part of the end or side of the house, and also to construct the ventilator to receive a single chimney-pipe, where a small tent is employed, or two chimney-pipes where a large tent is employed, the 40 opening or openings at the top of the tent for the stovepipes being closed by a hinged cover when the stoves are not in use.

I attain these objects by the mechanism 45 illustrated in the accompanying drawings, in which—

Figure 1 is a vertical longitudinal sectional view through a tent-cottage provided with my improved ventilator, which in this instance is shown with a single chimney-pipe.

50 Fig. 2 is a vertical longitudinal sectional view through a ventilator provided with two chimney-pipes. Fig. 3 is a vertical transverse sectional view through the ventilator on the line 3 3 of Fig. 2. Fig. 4 is a horizontal sec-

tional view on the line 4 4 of Fig. 2. Fig. 5 is a horizontal sectional view on the line 5 5 of Fig. 2. Fig. 6 is a bottom plan view of one of the ring-clamp plates which clamp the flap-rafters. Fig. 7 is a bottom plan view of one of the half-ring clamp-plates which is used in connection with the plate shown in Fig. 6. Fig. 8 is a sectional view illustrating the manner by which the side rafters are secured to the side strips of the ventilator-frames; and 65 Fig. 9 is a vertical sectional view through a portion of the tent, illustrating a hinged awning and manner of holding the same open.

Similar numerals of reference refer to similar parts throughout the several views. 70

Referring to the accompanying drawings, the numeral 1 refers to a tent-cottage, comprising the studding 2, the plate 3, the tent-rafters 4 and 4^A, and the flap-rafters 5 and 5^A. About a half of the height of the cottage or house is inclosed by clapboards 6, and the remainder is covered by a tent or canvas 7, which is secured at its lower edge to the clapboards, while the upper or ceiling portion is supported upon and secured to the 75 rafters 4 and 4^A. A flap or outer covering 8 is secured to the rafters 5 and 5^A. Air-space 9 is formed between the tent and flap, which communicates with the interior of the tent, 80 as will be hereinafter set forth. 85

The general construction of the house and the manner of securing the lower ends of the rafters is shown and described in my former patent, above referred to, and further reference to these points is unnecessary, my present invention being confined to combined 90 ventilator and rafter clamp.

The ventilator comprises a lower frame 10 and an upper frame 11, each of which is made up of side strips which are united at 95 each end by a pair of rafter-clamping plates, the upper frame 11 being supported a suitable distance above the lower frame by standards 12, a pair of which are secured near each end of the frame 10. Upon the upper frame 100 is secured a housing 13, at one or both ends of which is located a chimney-pipe 14, the housing and lower frame being provided with ventilating-doors, which are arranged and operated in a manner to be presently described. The lower frame 10 comprises the side strips 15, which are connected at each end on their under sides by a ring-plate 16 and on their upper sides by half ring-plates 17, the two ring-plates being used when the 110

ventilator is applied to a large tent, where two stoves would be required; but in a small tent where a single stove is required one ring-plate only is necessary, two half ring-plates being employed at the other end of the frame, it being understood that the ring-plates support and steady the stovepipes which pass through them. The upper ends of the end rafters 4 extend between the plates 16 and 17 and are tightly clamped in place by bolts 18, while the side rafters 4^a at their upper ends are provided with stud-screws 19, which extend through holes in the strips 15 and screw into nuts 20, which are rigidly secured in recesses 21 in the strips, and by this arrangement the rafters 4 and 4^a may be quickly and easily secured at their upper ends to the lower frame 10.

Above the openings in the ring-plates 16 are hinged doors 22, which rest upon the plates and cover the openings therein when stoves are not in use, and to the strips 15 and extending from one plate 16 to the other is secured a piece of screen-cloth 23. Midway 25 of the frame and extending from one side strip to the other is a cross-bar 24, and similar cross-bars 25 extend across the frame at the inner end of each ring-plate resting upon the top of the plate, the bars being above the screen-cloth, as shown in Fig. 2. To each edge of the central cross-bar 24 is hinged a door 26, and these doors each extend from the central cross-bar to the adjacent end cross-bar 25, and in connection with the doors or covers 22 completely close the air-exit at the top of the tent when they are down or in the position shown in Fig. 2.

A rope 27 is suitably secured at its ends to the doors 26 and passes up and over a pair of pulleys 28, which are secured to a cross-bar 29, secured between the side strips of the upper frame 11. It then extends down through an opening or openings in the cross-bar 24 and into the interior of the house within convenient reach of the occupant. By pulling upon the rope 27 either or both of the doors may be raised to ventilate the house, and when the rope is released the door or doors will fall by gravity and close the ventilator, and in order to insure the falling of the doors a blade-spring 30 is secured to the cross-bar 24, so that its ends will extend out over the doors, and as the doors are raised they will contact with these ends of the springs and bend them up, and the recoil of the spring when the rope is released will force the doors down.

The upper frame 11 is similar in construction to the frame 10 and is made up of side strips 31, which are connected at their ends by under half-ring plates 32 and upper ring-plates 33. These plates are similar to the plates 16 and 17 of the frame 10, with the exception that they occupy a reverse position, the ring-plates being above, and these plates

33 are provided on their outer edges with depending or introverted lips 33^a, while the half-ring plates 32 are provided with similar but upwardly-projecting lips 32^a. These lips 32^a and 33^a are oppositely positioned with respect to each other and occur at the points where the rafters 5 extend between the plates, and by screwing nuts on the ends of bolts 34, which extend down through both plates between the ends of the rafters, the lips 32^a and 33^a will be embedded in the ends of the rafters, and thus securely hold them in place between the plates.

The chimney-pipes 14 rest upon and are secured to the ring-plates 33 and are provided with lateral wings 35, which are secured to the ends of the sides of the housing 13 and also close the opening at each end thereof. The housing is preferably provided with a hipped roof, which is secured to the sides and 85 to end boards located adjacent to the chimney-pipes, and each side is provided with an outwardly-swinging door 36, which is hinged at its upper edge to the side, and these doors are opened and closed in the following manner: A rod 37 extends from the interior of the house up through slots in the cross-bars 24 and 29 to within a short distance of the top of the housing, and to the upper end of this rod is pivoted a pair of arms 38, which extend 90 downward and outward, and their opposite ends are pivotally connected at or below the horizontal centers of the doors 36. As the ends of the arms 38, which are pivoted to the rod 37, are on a higher plane than the ends 95 which are pivoted to the doors 36, it will be seen that by pulling down upon the rod, the arms will assume a horizontal position and thereby force the doors open. The rod is provided with a stop-pin 39, which contacts 105 with the cross-bar 29 and limits the downward movement of the rod, but this pin is so positioned that it does not engage the cross-bar until the ends of the arms which are pivoted to the rod are on a lower horizontal 110 plane than the ends which are pivoted to the doors, and in this position the pressure on the rod will be downward and the doors will thus be held open until the rod is pushed up again. To insure the closing of the doors and to prevent their being blown open, a coiled spring 115 40 is attached at its ends to the doors and secured midway of its length to the roof of the housing by a screw-eye or in any other suitable way, the spring being under sufficient tension to exert a strong pull on the doors, so that when the doors are opened the spring will be expanded or drawn out, and when the rod is pushed up to close the doors the spring will contract and act in conjunction with the 120 rod to close the doors, and hold them in a closed position. The doors or covers 22, which lie above the ring-plates 16, normally close the openings in these plates, and the space between the plates 16 and 17, where the 125 130

rafters 4 enter, is closed by semicircular flanged plates 41, which fit within the plate 17, their lower edges resting on the plate 16, while their flanges engage the plates 17, as will be seen by reference to Figs. 2 and 5. When a stove is used, the pipe 42 is shoved up through the ring-plate 16, and thereby lifts the door 22, which swings back on its hinges, as shown in dotted lines, Fig. 3, so as not to be in the way of the stovepipe. The stovepipe is pushed up into the chimney-pipe a sufficient distance to insure a good draft, and thus prevent smoke from settling in the house. When the doors 26 only are opened, the house is ventilated through the space between the tent and flap, and when the doors 36 are opened direct ventilation is obtained through the housing.

At any suitable point in the house and just above the floor-level I provide an additional ventilator which is constructed in the following manner: An opening of suitable size is made in the side of the house by cutting out a part of a clapboard, or, as illustrated in the drawings, a plurality of holes 43 are bored through the clapboards, and over these is secured a piece of wire-screen cloth 44. A hopper-shaped box 45, comprising a front board and end boards, is then secured to the clapboards, so as to inclose the holes 43, and the top of the box or ventilator is closed by a hinged cover 46, which may be opened when it is desired to admit fresh air into the house, this ventilator being especially serviceable at night should it be desired to close the door and windows.

In order to insure an abundance of air and light, I provide a window at any suitable point, preferably on one side of the door of the house, over which is secured a piece of wire-screen cloth 47. This window is divided centrally by a vertical strip 48, which extends from top to bottom and is provided at a point, preferably at or below its center, with a rectangular aperture 49, at the lower edge of which and on the inner side of the strip is secured a metal plate 50, the upper edge of which extends a slight distance above the lower edge of the aperture 49. To the outside of the window is hinged at its upper end a canvas-covered frame 51, which normally forms part of the side of the house. The frame 51 is also divided centrally by a strip or bar 52, to which is secured a right-angled hinge-plate 53, the projecting portion of which extends through the aperture 49 of the strip 48 when the frame is down or in a closed position. To the plate 53 is hinged one end of a bar 54, the other end of which extends through the aperture 49 and is provided with a groove 55, which is engaged by the plate 50 to hold the awning out or in an open position, but when it is desired to close the window the inner end of the bar 54 is raised slightly, so as to disengage its groove from the plate 50,

when the awning will drop by gravity, and the projecting end of the hinge-plate 53 will extend into the aperture 49 of the strip 48, permitting the bar to be swung up, so that its opposite end may be secured in any preferred way, preferably by being engaged by a hook or staple, thus preventing the opening of the awning from the outside.

The herein-described tent-cottage with its improved means of ventilation and other features forms a convenient and practical house for camping parties and also for invalids, and when not in use the house may be quickly and easily taken down and packed so as to occupy but a small amount of space.

Having described the invention, what I claim as new, and desire to secure by Letters Patent, is—

1. In a tent-cottage, the combination with an inner and outer set of rafters, of frames clamped to the upper ends of the rafters, each comprising side strips, and a pair of plates at each end, between which the ends of the rafters are clamped, one plate in each pair being in the form of a ring, while the other is in the form of a half-ring; swinging covers above the ring-plates of the inner frame, which normally close the openings therein; outwardly-swinging ventilating-doors in said frame, and means for opening said doors; a housing upon the outer frame, having outwardly-swinging doors; means for opening and closing the doors, and a chimney-pipe at the end of the housing, above the openings in the ring-plates of the two frames.

2. The combination with a tent-cottage of the character described, having inner and outer rafters and a canvas covering for each, of a ventilator therefor, comprising inner and outer frames, which are clamped respectively to the upper ends of the inner and outer rafters, each frame comprising side strips and a pair of rafter-clamping plates at each end, one of which is in the form of a ring while the other is in the form of a half-ring; hinged covers which normally close the openings in the rings of the inner frame; outwardly-swinging doors in said frame communicating with the space between the two sets of rafters, and means comprising rope and pulleys for operating the doors; a housing on the outer frame having outwardly-swinging doors, and means for operating the doors comprising arms pivoted at their outer ends to the doors; a rod extending up through the frames, to the upper end of which the inner ends of the arms are pivotally secured, and chimney-pipes at the ends of the housing, in line with the ring-plates.

3. In a tent-cottage of the character described, the combination with the inner and outer rafters, of frames secured at the upper ends of the rafters, comprising side strips and end clamping-plates, which clamp the rafters, and which are provided with stovepipe-

openings; hinged covers which normally close the said openings; a cross-bar midway of the inner frame; doors hinged to the cross-bar, and a screen-cloth below the doors; a cross-bar midway of the upper frame and a pair of pulleys secured thereto; a flexible connection secured at its ends to the doors, the remaining portion being passed over the pulleys and extending in a loop into the interior of the house; a housing upon the upper frame, having outwardly-swinging doors, and a chimney-pipe at each end of the housing in line with the openings in the clamping-plates; a rod which passes up through openings in the cross-bars, and into the housing; arms pivoted at their inner ends to the rod, and at their outer ends to the doors in the housing, said arms being adapted to push the doors open when the rod is pulled down, and springs for insuring the closing of the doors.

4. In a tent-cottage, having an inner and outer set of rafters, a ventilator therefor, comprising horizontal frames, each comprising side strips, and a pair of clamping-plates at each end, one of each pair being in the form of a ring, while the other is in the form of a half-ring, the said plates being adapted to be clamped upon the ends of the rafters, while those of the upper frame are provided on their edges with introverted lips which cut into the rafters; hinged doors upon the lower frame, and means for operating them; a housing on the upper frame having outwardly-swinging doors, and means for operating them; a chimney-pipe at each end of the housing in line with the ring-plates; hinged covers which normally close the ring-plates of the lower frame, and semicircular plates

which rest upon the said ring-plates and close the openings at the ends of the frame.

5. In a ventilator for tent-cottages, a horizontal frame, comprising side strips and a pair of clamping-plates at each end; a cross-bar in said frame, outwardly-swinging doors hinged to said cross-bar, means for operating the doors, and a spring for insuring the closing of the doors.

6. In a ventilator for tent-cottages, a horizontal frame comprising side strips, connected at their ends by pairs of dished clamp-plates, the lower plates being in the form of rings, while the upper plates are in the form of half-rings; hinged covers for the openings in the ring-plates; outwardly-swinging doors hinged to the frame and means for operating them; standards secured to the frame, and a similar frame secured to the top of the standards, the clamp-plates of which are reverse in position; a housing upon the upper frame having outwardly-swinging doors; chimney-pipes secured to the ends of the housing and resting upon the ring-plates; a rod extending into the housing, having arms pivoted thereto, which extend downward and outward, and are pivoted at their opposite ends to the doors; a pin in the bar, and an abutment with which said pin contacts, to limit the downward movement of the bar, and a spring for normally holding the doors in a closed position.

In testimony whereof I affix my signature in presence of two witnesses.

CHRISTOPHER SCHRAM.
